FAN

William Anthony Jones, West New Brighton, N. Y.

Application May 23, 1932, Serial No. 612,952

15 Claims. (Cl. 230—122)

My invention relates particularly to fans which receive gas at one side and discharge it at the other side and is a modification of that described in United States Patent #1,447,554 issued to me **5** March 6, 1923.

This modification consists in making the angularity of the stationary blades and of the moving blades each different for different distances from the center of the shaft so that for a definite **10** volume of gas and speed of fan, the resulting velocity of the gas will be the same for all distances from the center of the shaft, with resulting reduction in eddies and in friction loss.

This result may be obtained without much **15** thrust on the fan wheel bearings by making the wheel blades with a retreating angle at their outer radius and an advancing angle at their inner radius, so that the resulting axial thrusts on the fan wheel about neutralize each other. Nearly **20** all of the thrust is on the stationary blades.

Having in mind that the energy of motion and the pressure against which the motion will drive a gas is as the square of the velocity, the desirability of having the same velocity at all radii is **25** evident. If the velocity were directly as the radii so that the velocity at the outer radius was, for instance, six units while the velocity at the inner radius was five units, then the squares of these quantities would be as thirty-six is to twenty-five, **30** which would be the relation of the pressure at the outer radius compared to that at the inner radius.

Referring to the accompanying drawings;

Fig. 1 is a longitudinal section of a two-stage fan with stationary blades and with chords of **35** curved moving blades each having different angularities which compensate for the different speeds of the inner and the outer radii of the fan wheel.

Fig. 2 is a part end view of the fan shown in **40** Fig. 1.

Fig. 3 is a part development of the side view of this fan, showing shape of blades and openings for discharge of dust accompanied by some gas.

Fig. 4 and Fig. 5 are enlarged views of moving blades showing difference in angularity of chords at inner and at outer radii.

Fig. 6 is a longitudinal section of an eight-stage fan with surfaces of moving blades formed of **50** straight lines corresponding to the chords of the moving blades shown in Fig. 1 and otherwise identical with Fig. 1.

Fig. 7 is a part development showing a side view of the blades when the casing is removed to **55** indicate the shape of the blades, for the fan

shown in Fig. 6, being similar to Fig. 3 which is such a development for the fan shown in Fig. 1.

Fig. 8 is an enlarged view of stationary and moving blades of eight-stage fan, showing difference in angularity of lines at inside radius and **60** at outside radius, similar to Fig. 4.

Fig. 9 is an enlarged part sectional view through the forward and rear edges of the fan wheel and stationary cones showing the edges beveled.

Fig. 10 is a diagram showing lines representing **65** velocities of gas in its passage through the fan.

Figure 11 is a diagram showing lines representing velocities of gas in its passage through a fan, with a single row of moving blades, the fan being otherwise like that shown in Figs. 6, 7 and 8, with **70** blades formed of straight lines.

Figure 12 is a diagram showing the manner of applying the method of development disclosed in Fig. 11, to the multiple stage fan shown in Figs. **75** 6, 7 and 8.

Similar parts are referred to by similar numerals throughout the several views.

Referring to the drawings:

A fan wheel, 1, provided with blades, 2, is mounted on a shaft, 3. Shaft, 3, is driven from **80** shaft, 4, through gears, 5, and 6.

The fan casing is represented as having an inlet part, 7, an outlet part, 8, and a central part, 9, the latter made of pieces joined by flanges, 10, so that the parts can be conveniently removed. **85**

A conical shield, 11, concentric with the inlet part, 7, shields the central part of the fan wheel, 1. A similar shield, 12, shields the central part of the wheel in the outlet part, 8.

The space, 13, between the conical shield, 11, **90** and the inlet part, 7, of the casing, forms a passage of gradually decreasing area for gas as it approaches the fan wheel blades, 2. Stationary guide vanes, 14, in the space, 13, between the conical shield, 11, and the casing, 7, determine **95** the direction of flow of gas to the wheel, 1.

These guide blades, 14, are more oblique to the axis near the wheel, at the outside radius at, 15, than at the inside radius, at 16. Similar stationary guide vanes, 17, in the space, 18, between **100** the conical shield, 12, and the casing, 9, determine the direction of flow of gas as it leaves the blades of the wheel. These guide blades are also more oblique to the axis near the wheel at the outside radius, at 19, than at the inside radius, **110** at 20.

Inclination of the stationary vanes, 14, and, 17, with respect to the axis causes an axial thrust on the gas without a corresponding axial thrust on the fan wheel.

Edges of the wheel and of the plates forming the cones are beveled as shown at 21 and at 22 so that the wheel in effect overlaps the cones, tending to add to the pressure on the inlet side of the wheel and to decrease the pressure on the outlet side of the wheel. Wheel disks are provided with openings, 23, all to avoid difference in pressure on the two sides of the wheel.

Beyond the wheel a cylindrical baffle plate, 24, 10 is joined to the shell, 8, at, 25, and presents an opening at 26 for flow of dust-laden gas to openings 27 which discharge into a girth channel, 28, terminating in an outlet, 29.

Referring to the diagram, Fig. 10, line 30—31 15 being proportional to the inner radius, line 30—37 being proportional to the outer radius, then line 30—32, and line 30—38 represent the direction and velocity of flow of gas approaching the fan as determined by the inclinations of the stationary 20 blade at the inside radius and at the outside radius, and at an assumed volume equal to five-eighths of the free-flow volume of gas.

Lines 31—32, and lines 37—38 represent velocities, relative to the fan wheel, at the inside 25 and at the outside, of gas as it approaches the wheel.

Lines 32—33, and 38—39 represent velocities of gas, relative to the fan wheel, as it leaves the wheel.

30 Lines 33—34, and 39—40 equal in length to lines, 30—31, and 30—37, representing the velocities of the wheel blades at the inner radius and at the outer radius, when combined with lines 32—33, and 38—39 give lines 32—34, and 38—40 35 the velocities at the inside and at the outside which would obtain but for friction and but for the outlet pressure being greater than the inlet pressure.

The squares of the lengths of these lines compared to the squares of the lengths of lines 30—32, and 30—38 is proportional to the increase in pressure and friction loss.

The stationary vanes, 14, at the inlet side of the fan and, 17, at the outlet side of the fan, 45 determine the direction of gas flow as it approaches and as it leaves the fan.

Vanes, 17, are subject to a slight impact of gas, due to angles somewhat less than those between lines connecting points 35—32—36, and points 50 41—38—42. Other blades are without impact under the assumed conditions, except at their edges.

Absence of impact conduces to efficiency.

The construction shown gives a relatively long 55 axial travel for dust and gas and a relatively long time for the separation of the extremely small flocculent ash resulting from burning powdered coal. This is particularly the case for the multiple-stage fan which also results in greater pressure for a given speed.

As is known, the elastic air particles bounce from a surface against which they impinge at an angle equal to that with which they strike the surface, whereas particles of inelastic water slide from the surface and do not bounce from the surface. Accordingly, it will be readily understood that whereas for a propeller to act in water the pitch should be constant for all radii, this is not the case for a propeller to act in air.

70 For the apparatus described in this invention, making the sine of the angle between the stationary vanes and the axis directly proportional to the radius as shown, results in equal entering 75 velocity at all radii, for a given percentage of the

free flow volume, as diagram, Fig. 10, shows. The pitch increases towards the center.

In Fig. 11, I have shown how the inner and the outer lines of the stationary vanes and of the moving vanes of the fan are determined to give 80 line 32—134, representing gas velocity at the inner edge equal to line 38—140, representing gas velocity at the outer edge of the blade. Curved blades, 186, without batting or bouncing action, could be used instead of straight blades 2.

Figure 12 shows in heavy straight lines the shape of the inner edge of stationary and of moving blades using "bouncing action" and in light dotted curved lines shows the possible shape of the inner edges of the blades without "bouncing action" but arranged so that the gas slides onto and off of the blades without impact.

With the above in mind it is easy to understand why ordinary fans sometimes have an efficiency of only fifty three percent. This invention is an 95 effort to improve this condition without introducing disadvantages.

The bouncing action of the elastic gas particles when they strike against a surface at an angle, results in about the same change in velocity and 100 direction of flow with straight fan blades, like one of those shown in Figs. 6, 7 and 8, as for the curved blade, as shown in Figs. 1, 2 and 3, where impact is avoided for a given percentage of free flow volume. The curved blade also avoids 105 interfering with the flow from adjacent blades.

A spray of water or nonvolatile liquid, 50, discharged into the incoming gas from pipe, 51, may be used to give weight to extremely light dust and assist its separation. The spray of water may 110 also be used periodically to wash the inside surfaces of the apparatus.

Oil pipes, 52, 53, 54 and 55, convey oil for lubricating and cooling the bearings.

I claim:

1. In apparatus for causing gas to flow from a lower pressure to a higher pressure, the combination of a fan wheel with blades, a casing having a concentric conical shield at the inlet side of the fan wheel, a second conical shield at the 120 outlet side of the fan wheel, stationary vanes between the conical shields and the casing, the stationary vanes near the wheel being more oblique to the axis at their outer radius than at their inner radius, so that the sine of the angle of 125 inclination measured on a plane perpendicular to the radius is directly proportional to the radius.

2. In apparatus for causing gas to flow from a lower pressure to a higher pressure, the combination of a fan wheel with blades, a casing having 130 a concentric conical shield at the inlet side of the fan wheel, a second conical shield at the outlet side of the fan wheel, oblique stationary vanes between the conical shields and the casing, the stationary vanes near the wheel being more oblique to the axis at their outer radius than at their inner radius, so that the sine of the angle of the 135 inclination is directly proportional to the radius, the blades of the wheel being made so that lines connecting their forward and rear edges are at an advancing angle in the direction of motion for the inner radius and at a retreating angle for the outer radius.

3. In apparatus for causing gas to flow from a lower pressure to a higher pressure, the combination of a fan wheel with blades, a casing having a concentric conical shield at the inlet side of the fan wheel, a second conical shield at the outlet side of the fan wheel, oblique stationary vanes 140 between the conical shields and the casing, the stationary vanes near the wheel being more oblique to the axis at their outer radius than at their inner radius, so that the sine of the angle of the 145 inclination measured on a plane perpendicular to the radius is directly proportional to the radius.

150

- stationary vanes near the wheel being more oblique to the axis at their outer radius than at their inner radius, so that the sine of the angle of the inclination is directly proportional to the radius, 5 the blades of the wheel being made so that lines connecting their forward and rear edges are at different angles measured on a plane perpendicular to the radius for the inner radius and the outer radius.
- 10 4. In apparatus for causing gas to flow from a lower pressure to a higher pressure, the combination of a fan wheel with blades, a casing having a concentric conical shield at the inlet side of the fan wheel, a second conical shield at the outlet side of the fan wheel, stationary vanes between the conical shields and the casing, the stationary vanes near the wheel being more oblique to the axis at their outer radius than at their inner radius, so that the sine of the angle of the inclination is directly proportional to the radius, the blades of the wheel being made so that lines connecting their forward and rear edges are at different angles referred to a transverse plane for the inner radius and the outer radius, and the 20 blades of the wheel are made curved so that for a given speed of fan and volume of gas the curve of the blade will be tangent to the path of the entering gas relative to the blade at the inside radius and at the outside radius, as shown.
- 25 5. In apparatus for causing gas to flow from a lower pressure to a higher pressure, the combination of a fan wheel with blades, a casing having a concentric conical shield at the inlet side of the fan wheel, a second conical shield at the outlet side of the fan wheel, stationary vanes between the conical shields and the casing, the stationary vanes near the wheel being more oblique to the axis at their outer radius than at their inner radius, so that the sine of the angle of the 30 inclination is directly proportional to the radius, the blades of the wheel being made so that lines connecting their forward and rear edges are at different angles referred to a transverse plane for the inner radius and the outer radius, and the 35 blades of the wheel are made curved so that for a given speed of fan and volume of gas the curve of the blade will be tangent to the path of the entering gas relative to the blade at the inside radius and at the outside radius, and the action 40 of the blade imparts about the same velocity to the gas at the inner radius and at the outer radius.
- 45 6. In apparatus for causing gas to flow from a lower pressure to a higher pressure, the combination of a fan wheel with more than one row 50 of blades, a casing having a concentric conical shield at the inlet side of the fan wheel, a second conical shield at the outlet side of the fan wheel, and oblique stationary blades between the conical shields and the casing and between the rows of 55 blades of the wheel, the stationary vanes being more oblique to the axis at their outer radius than at their inner radius, so that the sine of the angle of their inclination measured on a plane perpendicular to the radius is directly proportional to the radius.
- 60 7. In apparatus for causing gas to flow from a lower pressure to a higher pressure, the combination of a fan wheel with more than one row of blades, a casing having a concentric conical shield at the inlet side of the fan wheel, a second conical shield at the outlet side of the fan wheel, oblique stationary blades between the conical shields and the casing and between the rows of 65 blades of the wheel, the stationary vanes near the wheel being more oblique to the axis at their 70 radius than at their inner radius, so that the sine of the angle of the inclination is directly proportional to the radius.
- 75 outer radius than at their inner radius, so that the sine of the angle of the inclination is directly proportional to the radius, the blades of each row of the wheel, being made so that lines connecting their forward and rear edges are at an advancing angle for the inner radius to thereby cause the gas to move circumferentially faster than the wheel and at a retreating angle for the outer radius.
- 80 8. In apparatus for causing gas to flow from a lower pressure to a higher pressure, the combination of a fan wheel with more than one row of blades, a casing having a concentric conical shield at the inlet side of the fan wheel, a second conical shield at the outlet side of the fan wheel, and oblique stationary blades between the conical shields and the casing and between the rows of 85 blades of the wheel, the stationary vanes near the wheel being more oblique to the axis at their outer radius than at their inner radius, so that the sine of the angle of the inclination is directly proportional to the radius, the blades of each row of the wheel, being made so that lines connecting their forward and rear edges are at different angles measured on a plane perpendicular to the radius for the inner radius and the outer radius.
- 90 9. In apparatus for causing gas to flow from a lower pressure to a higher pressure, the combination of a fan wheel with blades, a casing having a concentric conical shield at the inlet side of the fan wheel, a second conical shield at the outlet side of the fan wheel, stationary vanes between the conical shields and the casing, the stationary vanes near the wheel being more oblique to the axis at their outer radius than at their inner radius, so that the sine of the angle of the inclination measured on a plane perpendicular to the radius is directly proportional to the radius, an inlet for gas at one side of the fan wheel, 100 an outlet for gas at the other side of the fan wheel, and a second outlet for dust at a greater distance from the center than the first outlet.
- 105 10. In apparatus for causing gas to flow from a lower pressure to a higher pressure, the combination of a fan wheel with blades, a casing having a concentric conical shield at the inlet side of the fan wheel, a second conical shield at the outlet side of the fan wheel, and oblique stationary vanes between the conical shields and the casing, 110 the stationary vanes near the wheel being more oblique to the axis at their outer radius than at their inner radius, so that the sine of the angle of the inclination measured on a plane perpendicular to the radius is directly proportional to the radius, an inlet for gas at one side of the fan wheel, 115 an outlet for gas at the other side of the fan wheel, and a second outlet for dust at a greater distance from the center than the first outlet.
- 120 11. In apparatus for causing gas to flow from a lower pressure to a higher pressure, the combination of a fan wheel with blades, a casing having a concentric conical shield at the inlet side of the fan wheel, a second conical shield at the outlet side of the fan wheel, and oblique stationary vanes between the conical shields and the casing, 125 the stationary vanes near the wheel being more oblique to the axis at their outer radius than at their inner radius, so that the sine of the angle of the inclination is directly proportional to the radius, the blades of the wheel being made so, 130 that lines connecting their forward and rear edges are at an advancing angle so that the gas moves circumferentially faster than the wheel for the inner radius and at a retreating angle for the outer radius, an inlet for gas at one side of the fan wheel, an outlet for gas at the other side of the fan wheel, a second outlet for dust at a greater distance from the center than the first outlet.
- 135 12. In apparatus for causing gas to flow from a lower pressure to a higher pressure, the combination of a fan wheel with blades, a casing having a concentric conical shield at the inlet side of the fan wheel, a second conical shield at the outlet side of the fan wheel, and oblique stationary vanes between the conical shields and the casing, the stationary vanes near the wheel being more oblique to the axis at their outer radius than at their inner radius, so that the sine 140 of the angle of the inclination is directly proportional to the radius.
- 145 13. In apparatus for causing gas to flow from a lower pressure to a higher pressure, the combination of a fan wheel with blades, a casing having a concentric conical shield at the inlet side of the fan wheel, a second conical shield at the outlet side of the fan wheel, and oblique stationary vanes between the conical shields and the casing, the stationary vanes near the wheel being more oblique to the axis at their outer radius than at their inner radius, so that the sine 150 of the angle of the inclination is directly proportional to the radius.
